United States Patent Office

Des. 208,312
Patented Aug. 15, 1967

208,312

DOLL

Stanley A. Weston, 45 Remsen Road,
Great Neck, N.Y. 11024

Filed July 19, 1966, Ser. No. 3,134

Term of patent 14 years

(Cl. D34—4)

FIG. 1

I claim:

The ornamental design for a doll, substantially as shown and described.
